UNITED STATES PATENT OFFICE.

GEORGE H. GREENHALGH, OF HAZLETON, PENNSYLVANIA, ASSIGNOR TO ERNEST J. SWEETLAND, OF HAZLETON, PENNSYLVANIA.

DISTILLING DEVICE FOR LUBRICATING SYSTEM OF INTERNAL-COMBUSTION ENGINES.

Application filed May 6, 1922. Serial No. 558,979.

It is becoming more and more generally recognized that the presence of water and of lighter hydro-carbons such as gasolene and kerosene in the lubricating oil of internal combustion engines, seriously affects the lubricating qualities of the oil. In most internal combustion engines, particularly those used on vehicles, the crank case is a reservoir for the lubricating oil, with the result that the oil is constantly diluted, particularly in wintertime, by moisture condensed on the walls of the crank case and by gasolene, (and under some conditions by kerosene), which flows past the engine pistons and into the crank case.

It has been proposed to remove these diluting liquids from the lubricating oil of internal combustion engines by heating the oil and thus distilling out of it the water and the lighter hydro-carbons. The general object of the present invention is to provide a new and improved form of distilling device which is simple in construction, efficient in operation, and which is in the form of an attachment which can easily be applied to the oiling system of an internal combustion engine.

One of the characteristic features of my invention is a spherical distilling vessel adapted to be secured to and heated from the exhaust manifold of an internal combustion engine. Another characteristic feature of the invention resides in the provision of means, adapted to be located in the path of the exhaust gases through the engine exhaust manifold or pipe, for transmitting to the body of oil within the distilling device heat from the exhaust gases.

A further object of the invention is to provide means for controlling the influence of the exhaust gases on the distilling device in synchrony with the engine speeds, so that when the volume and temperature of the latter are particularly high the distilling device will not be overheated.

Various other objects and advantages of my invention will appear as the description proceeds.

The invention will be readily understood from the drawing in which Figure 1 shows, in cross-sectional elevation a distilling device embodying the invention, attached to the exhaust manifold of an internal combustion engine; Figure 2 is a cross-sectional

elevation of a modified form of distilling device, also embodying the invention; and Figure 3 is a cross-sectional elevation of another modified form of distilling device embodying the invention.

Referring to the drawings, all of the embodiments of the invention therein illustrated are characterized by what may be described as a spherical vessel within a spherical vessel or as a double-walled spherical vessel, and I regard this as a preferable construction, although some of the features of the invention are not necessarily confined to use with this form of vessel. In all of the forms shown, the inner spherical vessel is provided with intake and outlet openings for the oil and an outlet for the distilled vapor, and the outer spherical vessel is provided with intake and outlet openings for engine exhaust gases. Furthermore, in all of the forms illustrated, the distilling device is adapted to be mounted upon a pipe carrying exhaust gases such as the exhaust manifold of an internal combustion engine.

Referring first to that form of invention shown in Fig. 1, the distillator is shown as mounted upon an exhaust manifold 5 of an internal combustion engine from which the distilling device receives the exhaust gases for heating purposes. The distilling device is shown as comprising an inner spherical vessel 7 and an outer spherical vessel 9 arranged concentrically. The inner spherical vessel 7 is provided about midway of its height with an intake opening 11 and an outlet opening 13, which may be in the form of passages extending thru the outer and inner vessels and the space between them, and adapted to receive an inlet pipe 15 and an outlet pipe 17 for the oil which is to be treated. The inner vessel 7 is also provided near its top with an outlet opening 19 which may be in the form of a passage thru the walls of both vessels and the space between them, into which passage may be inserted a pipe 21 for carrying off the distilled vapor. The outer vessel 9 is also provided with an intake opening 23 surrounded by a neck 25 which may have a threaded end 27 as shown, or may be adapted in any other manner to be connected to the exhaust manifold 5 or other pipe carrying exhaust gases. The outer vessel 9 is also provided with an opening 29 into which may be screwed a pipe 31

adapted to carry off the exhaust gases which enter the space between the outer vessel 9 and the inner vessel 7 from the exhaust manifold 5. The pipe 31 may, as will be readily understood, be led to some other part of the pipe 5 carrying exhaust gases or may be left open at some location where escape of gases from it will not be objectionable. Within the neck 25 is located a valve 33 having a shaft 34, which may be journaled in holes oppositely located in the neck 25. At one end outside of the neck 25, the shaft 34 is provided with an arm 35 which is pivotally connected at 36 to a rod 38 connected to the throttle controlling means for the internal combustion engine in connection with which the distilling device is used. This connection between the valve 33 and the throttle controlling means for the engine is so arranged that the valve will move in synchronism with the movement of the throttle, thereby regulating the admission of exhaust gases within the space between the vessels 7 and 9. The wider the throttle is opened, the less is the amount of exhaust gas which is permitted to pass thru the distilling device; and, in this way, excessive heating of the device is prevented when the engine is running under conditions which produce an abnormally large amount of exhaust gases at abnormally high temperatures.

The form of the invention shown in Fig. 2 is also characterized by an inner vessel 40 and an outer vessel 41, pipes 42 and 43 for the oil, pipe 44 for the distilled vapor, a neck 45 having a threaded end adapted to enter a threaded hole with the exhaust manifold 46, and a pipe 47, thru which exhaust gases passing thru the distilling device may escape. With this form of the invention, a valve for controlling the admission of exhaust gases to the distilling device is not shown; but it is obvious that one similar to that shown in Fig. 1 may be inserted in the pipe 47. In order to provide for increasing the amount of heat which may be transmitted by the exhaust gases to the oil within the distilling device, the device shown in Fig. 2 is provided with hollow oil receiving means communicating with the inner vessel 40 and adapted to be located in the path of the exhaust gases passing thru the exhaust pipe or manifold 46. As shown, this means comprises a pipe 48 having a threaded end entering a hole in the bottom of the inner vessel 40 and extending downwardly thru the neck 45 into the exhaust pipe 46. This pipe 48 is preferably provided with a plurality of discs or fins 49 which are preferably integral with said pipe and serve to increase the capacity of the pipe for absorbing heat from the exhaust gases. With the form of the invention shown in Fig. 2, it will be understood that the oil in

the pipe 48 will be heated to a higher temperature than the oil within the vessel 40, and will rise into said vessel and will be replaced by cooler oil flowing from the latter. The heating effect of the exhaust gases upon the oil in the distilling device is thus increased.

The form of the invention shown in Fig. 3 may be regarded as a modification on the form shown in Fig. 2. The body of the distilling device of Figure 3 may be of the same form as the body of the device shown in Fig. 2, but instead of having the oil enter the device thru an opening in its side, this opening is closed by a plug 50 and the oil is fed in thru a pipe 51 which resembles an extension of the pipe 48 in the device of Fig. 2. This pipe 51, which is preferably provided with discs or fins 52, communicates with the bottom of the inner vessel 40', and extends thru the neck 45' of the outer vessel 41' and thru the exhaust manifold 46'. A gas-tight opening for the pipe 51 thru the bottom of the exhaust manifold 46' may be provided in any suitable manner, for example, by means of a sleeve 53 threaded into a hole in the exhaust manifold 46' and adapted to receive a packing 55 and a gland 54 which makes threaded connection with the inside of the sleeve 53.

In all forms of the invention illustrated, the body portion of the distilling device is preferably made of cast metal, which is possible since the inner spherical vessel is held in spaced relation with reference to the outer spherical vessel by the walls of the inlet and outlet passages for the oil and the distilled vapor. However, it is to be understood that the invention is not limited to this construction since obviously others may be employed.

With all of the forms of the invention, the distilling device may be arranged to receive either the whole or only a portion of the oil which is circulated in the lubricating system of the engine. As hereinbefore mentioned, the action of the distilling device is to cause the major portion of the lighter hydro-carbons and the water in the lubricating oil to be vaporized and removed from the oil. The distilled vapors may be carried off to any suitable point and either condensed or allowed to escape, as may be considered desirable. In the operation of the device the lower portion of the vessel 7 constitutes a heating reservoir and the upper portion a heated vapor dome in which the vaporized constituents of the oil in the reservoir are kept hot and prevented from condensing in the vessel and returning to the liquid oil in the reservoir.

While I have shown certain forms in which my invention may be embodied, it is to be understood that these are merely illustrative and that I intend in the appended

claims to cover all other forms which come in the spirit thereof.

What I claim is—

1. A distilling device adapted for use with the lubricating system of an internal combustion engine comprising a spherical vessel within a spherical vessel, the inner spherical vessel being provided with intake and outlet openings for the oil and an outlet for the distilled vapor, and the outer spherical vessel being provided with intake and outlet openings for engine exhaust gases.
2. A distilling device adapted for use with the lubricating system of an internal combustion engine comprising a spherical vessel within a spherical vessel, the inner spherical vessel being provided about mid-way of its height with oppositely located intake and outlet openings for the oil and near its top with an outlet for the distilled vapor, and the outer spherical vessel being provided with intake and outlet openings for engine exhaust gases.
3. A distilling device adapted for use with the lubricating system of an internal com-

bustion engine comprising a double-walled spherical vessel having thru both walls intake and outlet passages for the oil and an outlet passage for the distilled vapor, and having inlet and outlet openings thru the outer wall of said vessel one of which is adapted to be connected to a pipe carrying engine exhaust gases whereby the inner vessel may be entirely surrounded by the heating gases.

4. A distilling device adapted for use with an internal combustion engine, comprising a vessel having an outer wall and an inner wall spaced from one another, the outer wall substantially surrounding the inner, intake and outlet passages for the oil and an outlet passage for the distilled vapor being provided thru both of said walls, and oil receiving means spaced from but connected with said vessel and adapted to be interposed in a pipe carrying engine exhaust gases for heating the oil in said vessel.

In testimony whereof I have affixed my signature to this specification.

GEORGE H. GREENHALGH.
